UNITED STATES PATENT OFFICE

2,051,368

TEMPERATURE OVERLOAD RELAY

Charles H. Chapman, Scotia, N. Y., assignor to
 General Electric Company, a corporation of
 New York

Application October 5, 1935, Serial No. 43,741

4 Claims. (Cl. 200—124)

My invention relates to relays, more particularly to thermal overload relays having an inverse time characteristic, and has for an object the provision of a simple, reliable and inexpensive 5 relay of this type.

Various thermal overload relays have heretofore been proposed for protecting electrical energy translating apparatus against overloads of sufficient magnitude and duration to subject the 10 apparatus to dangerous temperatures. In applying thermal overload protection to such apparatus, it is often desirable or necessary that the entire control including the thermal relay, be immersed in a body of oil, as for instance, when the 15 apparatus to be protected is located in a hazardous place which is subject to explosive or corrosive atmospheres, and consequently considerable need has arisen for a thermal overload relay which will operate satisfactorily when immersed 20 in a body of oil.

The operation of thermal overload relays is to a large extent dependent upon the thermal properties of the medium surrounding the thermal working parts of the relay, and serious operating 25 difficulties are encountered, therefore, in the design of thermal relays for oil immersed operation. For example, the required watt input to operate a thermal relay in air is increased by approximately 400% when the relay is immersed 30 in a large body of oil.

This large watt input is of course unsatisfactory, and may be offset by thermally isolating the working parts of the relay from the large body of oil. Resort may be had, for this purpose, to the 35 practice of enclosing the thermal working parts of the relay in an oil-filled sealed container of thermal insulating material, so that the relay parts are thermally associated with only a small body of oil which is thermally isolated from the 40 main body of immersing oil.

Operating difficulties are again encountered, however, due to the susceptibility of the sealed container to leakage. Uniform operation of the relay requires that the thermal parts of the relay 45 be subjected at all times to the same ambient medium, and it will be apparent that if the sealed container develops a leak before the relay is immersed, or if the relay is removed from its oil bath after the leak occurs, the oil within the container 50 will drain out and the operation of the relay will be considerably affected by the air which enters the container. When the relay container is immersed in oil after the oil originally sealed therein has escaped, it will be found that the air which 55 is trapped within the container will substantially

prevent the container from refilling with oil, that is, a "diving-bell" effect exists. The construction of a tightly sealed container may also involve considerable expense.

Much is yet to be desired, therefore, in a thermal relay suitable for oil immersed operation in which provision is made for ensuring that the working parts of the relay are subjected at all times to the proper immersing medium, the relay being designed for low watt input when subjected 10 to that medium. Accordingly, it is a further object of my invention to provide a simple and inexpensive thermal relay the operation of which is reliable and uniform when immersed in oil. 5

In carrying out my invention in one form, I 15 provide walls of insulating material arranged to form a perforate container within which the thermal operating parts of the relay are disposed. The degree of perforation is such that when the relay is immersed in a body of oil, the container 20 will be substantially filled with oil, while the thermal operating parts of the relay and the relatively small body of oil within the container are thermally insulated from the main body of oil so as to minimize the transfer of heat there- 25 between. The thermal operating parts of the relay comprise a suitable thermally responsive device and a heater thermally associated therewith. More specifically, I provide a container formed of insulating material, at least two walls of the 30 container being provided with apertures of such size as to provide a degree of perforation which permits the container to fill with oil when it is immersed, and which prevents the entrapment of air within the container. Disposed within the 35 container, I provide a plurality of thermal devices each of which is provided with a heater. A pair of operating members extend through a wall of the container and are arranged to control suitable externally mounted contacts in accordance 40 with the thermal condition of either or both of the thermal devices.

For a more complete understanding of my invention, reference should now be had to the drawing in which Fig. 1 is an elevational view of a 45 relay embodying my invention; Fig. 2 is a sectional view taken along line 2—2 of Fig. 1; Fig. 3 is a sectional view taken along line 3—3 of Fig. 1 with certain parts broken away; and Fig. 4 is a somewhat diagrammatic view of my improved 50 thermal relay immersed in a body of oil within a tank or casing adapted to contain suitable load circuit controlling contactors or other devices.

Referring now to the drawing, I have shown my invention in one form as applied to a thermal 55

relay comprising a container 10 which includes a boxlike hollow member 11 formed of insulating material and provided with a cover member 12. As shown in Fig. 2, the opposed end walls 13 of the container are provided with relatively small apertures 14 so as to provide a perforate container. The size of the apertures 14 is such as to provide a predetermined degree of perforation so that when the container is immersed in a body of oil, the container will be substantially filled with oil, the non-air-tight construction preventing the entrapment of air within the container. Furthermore, the apertures 14 are of such small size that the small body of oil within the container is substantially thermally insulated from the main body of oil. Although the size of the apertures 14 may be varied somewhat in accordance with particular installations, I have found that for operation in an immersing medium having a viscosity of ordinary transformer oil, a diameter of $\frac{1}{8}$ " provides satisfactory operation.

Disposed within the container 10, I provide a plurality of thermal devices 15 and 16. Although these thermal devices may be of any suitable type, I have shown for purposes of illustration a pair of solder film overload relays of the type described and claimed in United States Patent No. 2,001,513 issued May 14, 1935 to Ernest Zurcher.

For the purposes of the present application each of the thermal devices 15 and 16 which are identical in construction, may be described as comprising a rotatable shaft or sleeve 17 which is normally soldered to a cylinder 18 supported on a base 19 formed of insulating material. The base 19 is provided with terminal screws 20 and 21 which serve to support conductors 22 and 23 each of which is provided with an extending portion arranged to engage a suitable terminal post. As shown, the conductor 22 engages the terminal post 24 which extends through and is secured to a wall of the container 10, and the conductor 23 engages a similar terminal post 25.

As described in the above referred to patent to Zurcher, a heating winding 26 encircles the cylinder 18, the ends of the heating winding being secured to and supported by a pair of hollow rivets 27 and 28 carried by a cover member 29. As shown, when the cover member 29 is positioned on the base member 19 and secured by suitable nuts 30 which engage the terminal posts 20 and 21, the rivets 27 and 28 respectively engage the conductors 22 and 23, and the heater winding 26 is therefore connected in circuit with the terminal members 24 and 25. It will be understood of course that when a predetermined current flows through the heating winding 26 for a definite time, the fusible solder which normally secures the shaft 17 to the cylinder 18 will be fused, and accordingly, the shaft 17 will be released for rotation relative to the cylinder 18.

While the thermal devices 15 and 16 may be arranged to operate any suitable contact mechanism, I have shown for purposes of illustration an arrangement by means of which a single pair of contacts 31 and 32 may be operated in accordance with the thermal condition of either or both of the thermal devices 15 and 16. As shown, each of the shafts 17 carries a toothed wheel 33, the toothed wheel 33 associated with the thermal device 15 being arranged to engage a rack 34 which carries the movable contact 31 and the toothed wheel 33 associated with the thermal device 16 being arranged to engage a rack 35 which carries the contact 32. As shown, a suitable insulating member 31a is interposed between the contact

31 and the rack 34 and a similar insulating member 32a is interposed between the contact 32 and the rack 35 so as electrically to insulate the contacts from the racks. It will be understood that the contacts are connected in a circuit to be controlled by suitable conductors (not shown), for example, in the circuit of the operating coil of a contactor which controls the load circuit in which the heaters 26 are connected.

The rack 34 is provided adjacent its upper end with a slot 36, and a screw 37 extending from a wall of the container 10 cooperates with the slot 36 to guide the rack 34 for reciprocal longitudinal movement. Likewise the lower end of the rack 35 is provided with a slot 38 which cooperates with a screw 39 to guide the rack 35. Extending outwardly from the rack 34 is a finger 40 to which is connected one end of an operating spring 41, the other end of the spring being connected to a similar finger 42 which extends outwardly from the rack 35. As shown, the lower end of the rack 34 extends through and is guided by a slot in the arm 42, a suitable spring 43 connected between the arm 42 and the lower end of the rack 34 serving to bias the rack into engagement with its associated gear 33. Likewise the upper end of the rack 35 extends through a slot in the finger 40, and a spring 44 biases the rack 35 into engagement with its associated gear 33. Suitable stop pins 45 and 46 associated respectively with the racks 34 and 35 are provided for limiting the reciprocal longitudinal movement of the racks when released by the thermal devices for operation by the spring 41.

It is now believed that a complete understanding of my invention may be had from a description of the operation. It will first be assumed that the container 10 has been immersed in a body of oil along with suitable load circuit controlling contactors and other devices, and that the thermal devices 15 and 16 have been connected in the circuit to be protected by means of the terminals 24 and 25. In Fig. 4, for example, I have shown the container 10 immersed in a body of oil 50 contained in a tank or casing 51. Preferably, the container 10 is mounted on a panel-board 52 by means of the terminal studs 24 and 25, and it will be understood that the casing 51 also contains the load circuit controlling contactors or other devices (not shown) immersed in the body of oil 50, the contacts 31 and 32 of the thermal relay being connected by flexible leads (not shown) in a suitable control circuit, for example, the energizing circuit of the contactors.

When the container 10 is immersed in the bath of oil, the apertures 14 will permit oil to flow into the container 10 and will also permit air to escape from the container 10 so that the container will be substantially filled with oil. So long as normal current flows in the circuit to be protected, the relatively small body of oil within the container 10 will absorb sufficient heat from the heater 26 so as to prevent operation of the thermal devices. Under continued normal current operating conditions, a condition of heat equilibrium is established, the oil within the container being heated to a temperature such that the rate of heat transmission from it to the outside body of oil is just equal to the rate of heat generation by the heaters 26. The amount of this heat, transmitted by conduction through the walls of the container and by the slight amount of thermal circulation of oil through the apertures 14, is so small, however, that the current operating

characteristics of the relay are substantially independent of the volume of the relatively large body of oil in which the relay, along with the load circuit controlling device, is immersed. Upon 5 the occurrence of an overload in the circuit, however, the heat generated by the flow of current through the heater 26 will be sufficient to fuse the solder normally securing the shaft 17 to the cylinder 18, and consequently, the shaft 10 17 and the gear 33 carried thereby will be released for rotation in accordance with the bias applied by the spring 41 and the associated rack.

If it is assumed that the thermal device 15 is heated sufficiently to release the associated gear 15 33 for rotation, it will be apparent that the rack 34 will be moved downwardly by the spring 41 so as to disengage the contact 31 from the contact 32. Likewise if the thermal device 16 is heated sufficiently to release its gear 33 for rotation, it will be apparent that the rack 35 will be moved upwardly by the spring 41 to move the contact 32 away from the contact 31.

The contact 31 may be reset after the thermal device 15 has cooled by pressing upwardly on 25 the lower end of the rack 34, the spring 43 permitting the rack to slide over the teeth of the gear 33. Similarly, the contact 32 may be reset after the thermal device 16 has cooled.

Although I have shown a particular contact arrangement and a particular type of thermal device, it will be understood that my invention is not limited thereto, since any suitable type of thermal device such, for example, as a bimetallic element may be mounted within the perforate 30 casing 10.

As used throughout the specification and the claims, the term "oil" will be understood to mean any suitable insulating liquid medium.

While I have shown a particular embodiment 40 of my invention, it will be understood, of course, that I do not wish to be limited thereto since many modifications may be made and I, therefore, contemplate by the appended claims to cover any such modifications as fall within the 45 spirit and scope of my invention.

What I claim as new and desire to secure by Letters Patent of the United States is:

1. A thermal relay for operation in a relatively large body of oil with oil immersed load circuit 50 controlling devices, said relay being immersed in the same body of oil as said load circuit controlling devices comprising a unitary structure including walls of thermal insulating material arranged to form a perforate container, the degree of perforation being such as to permit said container substantially to fill with oil when said unitary structure is immersed, the relatively small body of oil within the container being thermally insulated by said walls from the main body of oil, a thermal device disposed within said container, and means within said container for heating said thermal device.

2. A thermal relay for operation in a relatively large body of oil with oil immersed load circuit 60 controlling devices, said relay being immersed in

the same body of oil as said load circuit controlling devices, comprising walls of thermal insulating material arranged to form a container, at least two of said walls having restricted apertures therein, said apertures being proportioned to permit said container substantially to fill with oil when said container is immersed in a body of oil, the relatively small body of oil within said container being thermally insulated by said walls from the main body of oil, a thermal element 10 disposed within said container, a heating winding disposed in thermal relation to said thermal element within said container, and means including circuit connections extending through a wall of said container for energizing said heating 15 winding thermally to influence said thermal element.

3. A thermal relay adapted for oil immersed operation comprising walls of thermal insulating material arranged to form a perforate container, 20 the degree of perforation being such as to permit said container substantially to fill with oil when said container is immersed in a body of oil, the relatively small body of oil within the container being thermally insulated by said walls from the 25 main body of oil, a thermal device within said container including a rotatable member extending through a wall of said container, fusible means normally restraining said member against rotation, heating means disposed within said 30 container for heating said fusible means to release said member, and circuit controlling contacts responsive to rotation of said member.

4. A thermal relay for operation in a relatively large body of oil with oil immersed load circuit 35 controlling devices, said relay being immersed in the same body of oil as said load circuit controlling devices, comprising walls made of heat insulating material forming a container, said 40 walls being provided with a relatively small aperture for admission of oil to fill said container when it is immersed but substantially preventing thermal circulation of oil between the oil in said container and the oil surrounding said container, a pair of switch contacts, heat responsive means in said container for controlling the operation of at least one of said contacts, current responsive heat generating means in said 45 container for heating said heat responsive means in response to the current in said heat generating means for operation of said contacts upon the occurrence of a predetermined current, said walls providing thermal insulation substantially to prevent the transfer of heat by conduction therethrough from the oil in said container to 55 the oil surrounding said container, said walls thereby serving to admit oil to fill said container when the container is immersed while thermally isolating the oil in said container from the oil surrounding said container so that the current 60 responsive operating characteristics of said relay are substantially independent of the volume of the body of oil in which it is immersed.

CHARLES H. CHAPMAN. 65
